UNITED STATES PATENT OFFICE.

WALTER A. DOVASTON, OF NEW YORK, N. Y.

BOTTLE CLEANER.

Application filed November 1, 1926. Serial No. 145,605.

This invention relates to a new and improved device for cleaning and drying the interior of bottles and in particular to the type having a narrow opening or orifice.

5 A particular object of the invention is to provide a cheap and simple device which may be readily inserted through the narrow neck of vessels or bottles and through the medium of which the whole of the interior 10 surface of the narrow necked vessel, bottle or flask may be readily cleaned and dried.

A still further object of the invention is to provide a simple device which will not get out of order and which can be readily 15 manipulated to thoroughly cleanse the interior surface of the vessels in connection with which it is used.

To enable others skilled in the art to fully comprehend the underlying features of my 20 invention that they may embody the same in the various modifications in structure and relation contemplated, a drawing depicting a preferred form has been annexed as a part of this disclosure and in such drawings, 25 similar reference characters denote corresponding parts throughout all the views, of which,

Figure 1 is a view in elevation showing my improved bottle cleaner in its normal 20 position, the outline showing how the same would be manipulated to be placed within the narrow neck of a bottle or other vessel.

Figure 2 is a view in sectional elevation showing the interior working parts of my 35 device and the construction of the cleaning or drying pad.

Figure 3 is an enlarged, detail view, a part thereof being shown in section, to illustrate the connection of the pad carrying 40 member with the frame or housing of the bottle cleaner, and

Figure 4 is a view, looking at Figure 3 from the left hand side, showing how the two parts, namely, the housing and the pad carrying member, appear when assembled, 45 and as seen in Figure 3.

Referring in detail to the drawings, 5 indicates a stationary handle which is provided with a central bore 6, in which is inserted the end of a housing tube 7, the same being riveted over, as at 8, on the top of the handle whereby it is held in fixed position therein. This tube is of an extended nature and in its main portion is round but at its lower end is of square formation and one side wall thereof in the squared portion 9 is

cut away to provide an opening as at 10. The side walls 11, formed by the squared end of the tube providing therebetween a pivot support in which is held a pivot pin 12, the upper end of the housing tube 7 has positioned therein in sliding fit, an inner, movable tube 13 which extends beyond the riveted end 8 of the housing tube 7 and fits tightly within a bore 14 formed in an upper, movable, operating handle 15. This inner tube 13 being held in position through the medium of a rivet or other fastening pin 16 which passes through the turned over end 17 of a push rod 18, which fits within the inner tube 13 and in its lower end, which is disposed within the open portion of the lower end of the housing tube 7, is bent arcuately as at 19 so that when it is in one of its operating positions, it will not interfere with the pivot pin 12, hereinbefore referred to. This push rod 18 at its lower end is provided with an eye 20 which fits around a pin 21 secured in the opposite side wall of the square end 22 of a movable pad carrying arm 23.

This pad carrying arm 23 at its outer end is tubular and is flared as at 24 to provide a seat for the cleansing pad 25, the same being held in position through the medium of a screw 26 which is held in threaded relation with the end of the arm 23. This pad may be made up from a plurality of leather disks or disks of any suitable material adapted for cleansing or drying the interior of a vessel and it is to be particularly understood that I am not limited to the showing of a plurality of disks but may use a mop or sponge or any other suitable device of a cleaning character. The lower end of the arm 23 is squared and is open at one side as is the case with the housing tube 7. The end of the arm 23 is of smaller diameter but being large enough to fit snugly within the end of the housing tube 7, where it is pivoted on the pivot pin 12, as clearly shown in Figures 2, 3 and 4.

It is evident that the arm 23 may be swung to the position shown in Figure 2 or may be positioned at any angle from the one illustrated, to a position in alignment with the housing tube, as indicated in outline in Figure 1. However, in order to normally maintain the cleansing pad carrying arm in the position shown in Figure 2, I provide a compression spring 27 which is positioned 105 exteriorly of the housing tube 7 and dis-

posed between the stationary handle 5 and the operating handle 15. The tendency of the spring, as is apparent, will be to maintain the handles in their separated position, the limit of their separation being dependent upon the angular position of the pad carrying arm 23, as illustrated in Figure 2. It is evident, then, that by operating movable handle 15 toward handle 5, that the pad carrying arm 23 will assume a position in alignment with the housing tube 7, as indicated in outline in Figure 1, at which time, it may be passed through the narrow neck or orifice of a vessel to be cleaned. 15 When the same has been passed into the interior of the vessel, the movable handle 15 may be released until the pad carrying arm 23 assumes the position where the pad itself is in contact with the wall of the vessel to be cleaned. It is evident that when the arm 23 is in its vertical position in alignment with the tube 7, that the out-struck arcuate portion 19 of the push rod 18 will fit snugly about the pivot pin 12 and the operation of the arm 23 in its vertical movement will not be interfered with, it being of course understood that the flexible nature of the push rod will allow the arcuate movement of the pad carrying arm 23 about the pivot pin 12, there being sufficient room within the housing tube 7 to permit sidewise movement of the push rod, which is necessary during the arcuate movement of the pad carrying arm 23, as before referred to.

It is evident that by suitably manipulating the handle 15 when the cleaning or drying pad is inside the vessel, the angle between the two parts of the articulated rod 40 may be so varied as to enable the cleaning or drying pad to be drawn into contact with any portion of the interior surface of the vessel to be cleaned or dried.

It is evident, therefore, that I have provided an improved cleaning and drying device which may be inserted through the narrow neck of vessels, such as flasks, bottles or the like and through the medium of which the whole of the interior surface of the vessel may be cleansed or dried as the case may be.

It is also evident that I have provided a cleaning implement which may be made up cheaply and which, being constructed of few parts will not readily get out of order and which can be manipulated as desired to operate upon the interior surface of the vessel to be cleaned.

While I have illustrated and described my invention with some degree of particularity, I realize that in practice various alterations therein may be made. I therefore reserve the right and privilege of changing

the form of the details of construction or otherwise altering the arrangement of the 65 correlated parts without departing from the spirit of the invention or the scope of the appended claims.

Having thus described my invention, what I claim as new and desire to secure by 70 United States Letters Patent is:—

1. A vessel cleaning implement comprising a tubular housing, a handle at one end thereof, an inner tube slidable in the housing, a handle at one end of said inner tube, a 75 spring between said handles, a pad carrying arm, pivoted in said housing, means secured to said inner tube handle for operating said pad carrying arm, a pad at the end of said arm and a threaded member for holding the 80 pad in position on the end of the arm and said arm being adapted to be moved to a position in alignment with said tubular housing.

2. A vessel cleaning implement comprising 85 a pair of telescoping tubes, a pair of handles connected respectively to the tubes, a coil spring arranged in abutting relation with both of said handles, and a cleaning device swingingly connected to one of said tubes, and a link connecting the cleaning device to the other tube.

3. A vessel cleaning implement comprising 90 an outer tube, a handle secured to one end of the tube, an inner tube slidably mounted within the outer tube, a handle secured to the inner tube in spaced relation with said first mentioned handle, a spring encircling said inner tube and having abutting relation with both of said handles, an 100 arm swingingly associated with the outer tube, a cleaning pad secured to said arm and an operating rod secured to said second mentioned handle and having a pivotal connection with said arm for giving movement 105 to the latter in the movements of the handles towards and away from each other.

4. A vessel cleaning implement comprising 110 an outer tube, a handle secured to one end of the tube, an arm pivotally connected to the other end of the tube, an inner tube slidably mounted on the outer tube, a handle secured to one end of the inner tube in spaced relation with the first mentioned handle, a spring encircling said inner tube and abutting both of said handles, an operating rod 115 slidably mounted within the tubes with one end connected to the second mentioned handle and its other end pivotally connected to said arm, a cleaning pad abutting a flared end of said arm and a screw passed through said pad and threaded to the flared end of said arm.

In testimony whereof I affix my signature,

WALTER A. DOVASTON. [L. s.]
